UNITED STATES PATENT OFFICE.

HARRY C. MALLORY, OF NEW YORK, N. Y.; SUE R. MALLORY ADMINISTRATRIX OF
SAID HARRY C. MALLORY, DECEASED.

CONDENSER FOR ENGINE-COOLING SYSTEMS.

Application filed July 30, 1921, Serial No. 488,595. Renewed December 6, 1923.

To all whom it may concern:

Be it known that I, HARRY C. MALLORY, a citizen of the United States, and resident of New York city, in the county of New York and State of New York, have invented certain new and useful Improvements in Condensers for Engine-Cooling Systems, of which the following is a specification.

My present invention consists in an improved condenser adapted to receive vapor and boiling liquid through an inlet at its top, and to condense the vapor, and to pass the unvaporized liquid into the condenser hot well without contact with the condensing surfaces and the consequent reduction of their condensing capacity. My invention is especially adapted for use in an engine cooling system of the type disclosed in my prior application, Serial No. 482090, filed July 2, 1921, but is not necessarily limited to such use. The distinguishing characteristic of my present invention is the provision in water flow and steam distributing channels extending vertically downward past the condensing surfaces of baffles which retard the flow through said channels and thereby facilitate the liberation of vapor carried by the liquid and also increase the cooling of the liquid itself as may be desirable in some cases.

The various features of novelty which characterize my invention are pointed out with particularity in the claims annexed to and forming a part of this specification. For a better understanding of the invention, however, and the advantages possessed by it, reference should be had to the accompanying drawings and descriptive matter in which I have illustrated preferred embodiments of my invention.

Of the drawings:

Fig. 1 is an elevation of an engine cooling system in which my improved condenser is employed, the condenser being shown in section on the line 1—1 of Fig. 2;

Fig. 2 is a section on the line 2—2 of Fig. 1;

Fig. 3 is a partial section taken similarly to Fig. 2 illustrating a modified construction; and

Fig. 4 is a partial section on the line 4—4 of Fig. 3.

In Figs. 1 and 2 of the drawings I have shown my improved condenser employed in an engine cooling system comprising a cool-

ing liquid jacket A for the cylinder A⁵ of an ordinary internal combustion automobile engine. An inlet A' is provided at the bottom of the jacket space for the cooling liquid which will ordinarily be water or a water and alcohol mixture, and A² represents a jacket outlet for vapor which also serves as the overflow outlet for the cooling fluid. The outlet A² is connected by a conduit C, which may advantageously include a flexible coupling C' to the upper chamber B² of the condenser. The hot well B⁴ of the condenser B is connected to the jacket inlet A' by a return connection including pipe sections D and D' and a circulating pump E which is driven from the engine shaft through the reducing gear E', the latter also driving the usual fan G through a belt G. An air pipe H running from the condenser to the suction intake manifold L of the engine forms a means for withdrawing air from, and maintaining a vacuum in the condenser. As shown the pipe H extends through the condenser and is formed with an air inlet port H' at its under side. The air pipe H is shown as provided with a steam trap or valve I permitting the escape of air but restricting the escape of steam from the condenser through the pipe H. As shown the pipe section D' comprises a goose neck portion extending to the top of the jacket and connected to the condenser by a vent pipe F to prevent the jacket from draining into the condenser when the circulating pump is stopped. M represents a safety valve limiting the pressure in the condenser and I represents a vacuum relief valve, preferably adjustable, which is adapted to open and admit air to the condenser when the pressure therein falls to a predetermined minimum.

The condenser is provided with distributed condensing surfaces B' which advantageously, as shown, are formed by horizontal pipes having their ends expanded and connected together to thereby form portions of the front and rear walls of the condenser shell. In the respect noted the condenser is similar in construction to the radiator commonly used in an automobile cooling system of the water circulation type. The tubes B' are spaced away from the top of the condenser shell to provide the inlet chamber B², and are spaced away from the

2 bottom of the condenser shell to provide the hot well space B^4 , and are spaced away from the side edges of the condenser shell to provide channels B^3 . The latter form paths 5 of flow for unvaporized liquid entering the chamber B^2 , and also form channels for distributing vapor into the side edges of the intertube space. B^{10} represents a baffle extending over the bank of tubes B' at the 10 bottom of the chamber B^2 , and R represents rain plates for diverting liquid of condensation formed in the upper portion of the intertube space into the channels B^3 and thereby preventing it from flowing over 15 the lower tubes. In so far as above described the condenser shown is like that disclosed in my prior application, Serial No. 482,090.

The condenser forming the subject matter of the present invention differs from 20 that disclosed in my prior application however in that baffles are provided for retarding the downward flow of liquid and vapor through the channels B^3 , thereby facilitating the liberation of vapor from the liquid 25 and permitting of an increased cooling effect on the liquid without any such sacrifice of condensing capacity as would result from causing the liquid to flow over all or a considerable portion of the tubes B' .

30 In the construction shown in Figs. 1 and 2 in each channel B^3 is a series of baffles O inclined downwardly from the outer edge of the condenser shell, and a second series of baffles O' which alternate with the baffles O 35 and are inclined downwardly from the adjacent edge of the bank of tubes. Advantageously as shown baffle O' is provided with an upturned portion O^2 preventing liquid running off the baffle O immediately above, 40 from splashing into the intertube space.

In the modified construction shown in 45 Figs. 3 and 4 the baffles O and O' are replaced by two series of baffles O^3 and O^4 which are oppositely inclined downwardly from the front and rear walls of the condenser shell.

In the contemplated operation of the cooling system shown in the drawings, liquid is forced into the jacket through the inlet A' 50 at a rate substantially in excess of the rate at which liquid will be evaporated in the system by the heat absorbed in the jacket A . In consequence in regular operation liquid flows continually out of the top of the jacket 55 through the outlet A^2 . With suitably designed apparatus under certain conditions of operation all of the vapor generated by the heat absorbed in the jacket will be liberated in the jacket A or in the conduit 60 C to the condenser so that the discharge from the latter into the condenser space C^2 will comprise a lower stream of liquid and an upper stream of vapor. Under other conditions, however, the discharge into the condenser chamber C^2 from the conduit C will

consist wholly or mainly of boiling liquid. In any case the liquid and any free vapor in the chamber C^2 will pass from the latter downward into the channels B^3 . The baffles O and O' , or O^3 and O^4 provided in accordance with the present invention, break up the streams of liquid and give both the time and broken character of flow through the channels B^3 desirable for the complete liberation of vapor from the liquid and will 70 substantially restrict the flow of vapor directly into the condenser hot well. The retarding of the liquid flowing through the channels B^3 tends to an increased cooling of 75 the liquid which is desirable in many cases. 80

While in accordance with the provisions of the statutes I have illustrated and described the best form of my present invention now known to me, it will be apparent to those skilled in the art that changes may be made in the form of my invention without departing from the spirit of my invention as set forth in the appended claims, and that certain features of my invention may sometimes be used to advantage without a 90 corresponding use of other features.

Having now described my invention, what I claim as new and desire to secure by Letters Patent, is:

1. In an engine cooling system, the combination with a liquid cooling jacket having a top outlet, of a surface condenser comprising distributing condensing surfaces arranged to provide one or more distributing channels leading downward past the condensing surfaces, a connection from said outlet to the upper portion of the condenser for passing liquid and vapor into the latter, means within the condenser for diverting liquid away from said condensing surfaces 100 and into said channels, baffles for retarding and breaking up the streams of liquid flowing downward through the channels, and means for returning liquid from the bottom 105 of the condenser to the jacket.

2. In an engine cooling system, the combination with a liquid cooling jacket having a top outlet, of a surface condenser comprising distributing condensing surfaces arranged to provide one or more distributing channels leading downward past the condensing surfaces, a connection from said outlet to the upper portion of the condenser for passing liquid and vapor into the latter, means within the condenser for diverting liquid away from said condensing surfaces 115 and into said channels, baffles for retarding and breaking up the streams of liquid flowing downward through the channels, means for admitting air to and withdrawing it 120 from said condenser to maintain a regulated vacuum therein, and means for returning liquid from the bottom of the condenser to the jacket.

3. A condenser for an engine cooling sys- 125

tem, comprising a shell and distributed condensing surfaces arranged therein to provide an upper inlet space, a lower hot well space, and channels leading downward past the condensing surfaces from the inlet space to the hot well, means for diverting liquid entering said inlet space into said channels, and baffles in said channels arranged to retard and break up streams of liquid flowing downward through the channels. 10

Signed at New York, in the county of New York and State of New York, this 28th day of July A. D. 21.

HARRY C. MALLORY.
